(57) **CLAIM**

The ornamental design for a motorcycle suspension, as shown and described.

DESCRIPTION

FIG. 1 is a bottom, front left perspective view of a motorcycle suspension according to my invention.

FIG. 2 is a front, elevation view of the motorcycle suspension.

FIG. 3 is a top plan view of the motorcycle suspension.

FIG. 4 is a bottom plan view of the motorcycle suspension.

FIG. 5 is a left side, elevation view of the motorcycle suspension, the right side, elevation view being a mirror image thereof; and,

FIG. 6 is a rear elevation view of the motorcycle suspension.
